(57) **CLAIM**

The ornamental design for a LED mask as shown and described.

DESCRIPTION

FIG. 1 is a bottom perspective view of a LED mask showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof; and,

FIG. 9 is an enlarged detail view taken from portion 9 of FIG. 1.

The broken lines in the drawings depict portions of the LED mask that form no part of the claimed design.

The broken line circle in FIGS. 1 and 9 define the bounds of the enlargement and form no part of the claimed design.

1 Claim, 9 Drawing Sheets
